CAR RETARDER CONTROL SYSTEM

Reginald F. Albrighton, Rochester, N. Y., assignor to
General Railway Signal Company, Rochester, N. Y.

Application June 6, 1955, Serial No. 513,321

7 Claims. (Cl. 104—26)

This invention relates to car retarder control systems for railroads, and it more particularly pertains to automatic release control for car retarders of the track brake type.

In a car retarder control system such as is disclosed in the U. S. patent application of Kendall et al., Serial No. 513,364 filed of even date with the present application, certain car retarders known as "group car retarders" are automatically operated to release cars at speeds selected in accordance with the performance of such cars in approaching the associated car retarders. If it is a relatively long cut of cars, however, that is being retarded, it is desirable to release the cut at a speed somewhat lower than the speed that would normally be selected by the automatic releasing means that is normally effective.

The present invention makes use of the detector track section for the track switch immediately preceding each of the group car retarders as a part of a detecting system to detect the presence of long cuts of cars as distinctive from short cuts. If successive cars are separated by a distance greater than the length of the detector track section, these cars are not detected as a long cut because a requisite for long cut detection is set up circuitwise wherein a long cut is detected only provided that the detector track section continues to be occupied until the first car of the cut arrives in immediate approach of the first of the group of car retarders.

An object of the present invention is to detect long cuts of cars as distinguished from successive spaced short cuts of cars.

Another object of the present invention is to release long cuts of cars in a car retarder at a different speed from the speed at which the cars would be automatically released if they were in short cuts.

Other objects, purposes and characteristic features of the present invention will be in part obvious from the accompanying drawings and in part pointed out as the description of the invention progresses.

In describing the invention in detail, reference is made to the accompanying drawings in which parts having similar functions are generally identified in the several figures by similar letter reference characters, and in which:

Figs. 1A and 1B when placed end to end illustrate somewhat schematically one embodiment of a system provided by the present invention for detecting long cuts of cars and governing the release of group car retarders in accordance with the detection of long cuts;

Figs. 2A-2J (there being no Fig. 2I) are track diagrams illustrating different stages in the progress of cuts of cars; and

Figs. 3A-3J (there being no Fig. 3I) are sequence charts illustrating the mode of operation of parts of the system under different traffic conditions.

For the purpose of simplifying the illustrations and facilitating in the explanation of the invention, various parts and circuits constituting the embodiment of the invention illustrated have been shown diagrammatically

2

and conventional illustrations have been employed, the drawings having been organized more with the purpose of facilitating an understanding of the principles and mode of operation of the invention than with the idea of illustrating the specific construction and arrangement of parts that would be employed in practice. The symbols (+) and (—) are employed to indicate connections to the positive and negative terminals of suitable batteries or other sources of direct current. The symbol (B—) is used to indicate connection to the negative terminal of the high voltage power supply used in connection with radar speed responsive apparatus.

With reference to Fig. 1A, the track layout with which one embodiment of the invention is associated is illustrated in part as comprising a stretch of track 10 to which tracks 11 and 12 are connected by track switches 3TS and 2TS respectively. The right hand ends of the tracks 10 and 12 are to be considered as forming respective classification tracks wherein freight trains are respectively made up in a classification yard.

According to actual practice, the track layout of a hump classification yard generally includes a relatively large number of classification tracks and track switches governing entrance thereto, and it is to be understood that the present invention is readily applicable to a classification yard of any particular size. The typical section of trackway illustrated in Fig. 1A, however, can be considered typical of a number of similar sections of trackway that are found in a complete classification yard layout. These larger track layouts generally have as many as eight or ten classification tracks that are fed from each stretch of track including one or more group car retarders such as the car retarders numbers 1 and 2 of Fig. 1A.

Car retarders Nos. 1 and 2 are disposed end to end respectively in the stretch of track 10 in the approach of the track switch 2TS as a means for providing final retardation for cars proceeding to classification tracks beyond the car retarders to the right.

Although the car retarders numbers 1 and 2 can assume a number of different forms, such as being of either the weight-automatic, or the spring-actuated type, for this embodiment of the present invention, it is assumed that these car retarders are of the type having spring actuated brake shoes wherein the degree of pressure applied is adjustable by power driven means. A suitable car retarder of this type is disclosed, for example, in the U. S. patent to W. K. Howe, No. 1,852,572, dated April 5, 1932.

Car retarder operating mechanisms as illustrated in block form, are provided for selectively operating the respective car retarders to different degrees of retardation or to release positions as required. These operating mechanisms can be controlled as is disclosed, for example, in the U. S. patent to W. K. Howe, No. 2,038,112 dated April 21, 1936.

For the embodiment of the invention illustrated in Fig. 1A, a weighing device WD is used at the entrance end of the car retarder No. 1 for determining the degree of retardation required for cars entering the group car retarders in accordance with the weights of approaching cars. This weighing device need not weigh the entire car, but can be constructed to respond to the weight applied by one wheel of a car as being indicative of the approximate weight that the car is carrying. This weighing device also serves as a means for rendering the operation of radar speed responsive apparatus effective to govern the release of the car retarders in accordance with the speeds of approaching cars.

Near the exit end of each of the car retarders is a directional antenna DA which is connected to suitable

radar speed responsive apparatus which is illustrated in Figs. 1A and 1B in block form. This radar speed responsive apparatus is assumed to be of the continuous wave radar type employing the Doppler frequency principle discussed in general terms in chapter 5 of the book entitled "Radar System Engineering" edited by Louis M. Ridenour and constituting volume 1 of the Radiation Laboratory Series published by the McGraw-Hill Book Company of New York. This radar speed responsive apparatus is sometimes called an "interferometer." A suitable type of interferometer for this purpose is disclosed, for example, in the U. S. application of H. C. Kendall et al., Ser. No. 359,162, filed June 2, 1953. The radar speed responsive apparatus assumed to be employed in the embodiment of the present invention illustrated in Figs. 1A and 1B is assumed to provide improvements over the above mentioned application of H. C. Kendall et al., Ser. No. 359,162 as is disclosed in the U. S. application of H. C. Kendall et al., Ser. No. 513,364 filed of even date with the present application.

Associated with each of the car retarders is a pair of weight relays W1 and W2 that are suitably controlled to distinctive conditions in accordance with the weight of an approaching car as may be determined by the weight detector WD. A heavy car is indicated when relay W1 is down and relay W2 is up; a medium weight car is indicated when both relays W1 and W2 are up; and a light weight car is indicated when relay W1 is up and relay W2 is down.

A speed relay S and an anticipation relay A are provided for each car retarder, these relays being controlled by associated radar speed responsive apparatus so as to be released upon passage of a car when the speed of a car is reduced to respective selected speeds. The anticipation relay A is controlled to release at a slightly higher speed than the speed relay S.

A check relay CK is provided for each of the car retarders for the purpose of rendering effective the automatic control of the associated car retarder in accordance with the speed of a car, only provided the car is immediately in approach of the associated car retarder.

An exit relay XR and an associated slow dropping away relay XP is provided for each of the car retarders for the purpose of restoring relays associated with the same car retarder to their normal positions after passage of a car.

A track relay TR is provided for a conventional detector track section T that is associated with the track switch 3TS. A slow pick-up back contact repeater relay TP is associated with track relay TR.

Track storage stick repeater relays TPS are provided for use in long cut detection, the number of relays TPS required being in accordance with the storage requirements for each particular yard based upon the maximum number of cuts of cars that would be expected to occupy the portion of trackway illustrated within car retarder No. 1 and in approach thereof. Each of the storage relays TPS has associated therewith a pair of transfer relays TN and TNP to facilitate the transfer of storages as a car progresses.

A manually operable control lever RCL is provided for each of the car retarders. This is a control switch having a position for automatic operation and separate positions for the respective degrees of operation of the associated car retarder that may be required for manual operation.

Having thus described in general the apparatus provided in accordance with the present invention, further detail consideration will be given as to the organization of the apparatus and the circuits involved when considering the mode of operation under various typical operating conditions.

Operation

A normal condition that the apparatus assumes when there are no cars present in the track layout is that which

is illustrated in Figs. 1A and 1B wherein all of the relays illustrated are in their deenergized positions except for the track relay TR which is normally energized according to usual practice for the control of track relays. It is assumed that normally the levers 1RCL and 2RCL are in their extreme left-hand positions which renders the control of the car retarders subject to automatic operation.

The car retarders are normally closed in accordance with the associated check relays CK being in their dropped away positions. This is primarily as a matter of safety to insure that there will always be braking available for a car, even though there might be a failure in the control apparatus. Thus, for example, energy is normally applied to control wire 4 through normally closed contact 8 of switch 1RCL and back contact 9 of the check relay 1CK. The closure of this circuit insures that the car retarder No. 1 is operated to its position of maximum retardation under normal conditions. It will be readily apparent that it could as well be normally operated to positions of lesser degree of retardation in accordance with the requirements of practice.

When a car approaches the group car retarders and enters the detector track section T as is illustrated in Fig. 2A, the detector track relay TR is dropped away, and the dropping away of this relay causes the picking up of the transfer relay 1TN. This relay is picked up by the energization of a circuit extending from (+), including back contact 13 of relay TP, back contact 14 of relay TR, back contact 15 of relay 1TN and lower winding of relay 1TN, to (-). The picking up of this relay closes a stick circuit at front contact 16 shunting back contact 15 of relay 1TNP out of the circuit just described. The relay 1TN is preferably made slow to drop away by the shunting of its upper winding through front contact 17.

The dropping away of the track relay TR also closes a circuit for the picking up of its back contact repeater relay TP through back contact 18, but the relay TP is sufficiently slow acting to allow time for the relay 1TN to be picked up and also to allow time for the energization of the relay 1TNP.

It is to be understood that the setting up of the storage for the car by the actuation of relay 1TN may be accomplished by transfer from a prior storage such as might be provided in automatic switching circuits, rather than in accordance with entrance to the track section T as has been shown and described.

Relay 1TNP becomes picked up in response to the picking up of relay 1TN by the energization of an obvious circuit for its lower winding closed at front contact 19 of relay 1TN. This relay when picked up is maintained energized by a stick circuit extending from (+) through back contacts 20 and 21 of relays 2TNP and 2TN connected in multiple, front contact 22 of relay 1TNP and lower winding of relay 1TNP to (-). Relay 1TNP is preferably made slow to drop away by the shunting of its upper winding through front contact 23.

Shortly after the relay 1TNP has been picked up, the relay TP becomes picked up, thus opening the circuit for the energization of relay 1TN at back contact 13. Relay 1TN then becomes dropped away.

The fact that the relay 1TNP has been picked up registers the presence of the car, and this information is stored by the relay 1TNP until the information can be transferred to the storage relay 2TNP that is more directly associated with car retarder No. 1. Inasmuch as the relay 2TNP is in its deenergized position under the assumed conditions of traffic, conditions are properly set up for transfer of the storage to the relay 2TNP.

Upon the picking up of relay 1TNP, the relay 2TN becomes energized by a circuit extending from (+), including front contact 24 of relay 1TNP, back contact 25 of relay 2TNP, back contact 26 of relay 1XR and lower winding of relay 2TN, to (-). The picking up of this relay establishes a stick circuit at front contact 27

shunting contacts 25 and 26 of relays 2TNP and 1XR respectively out of the circuit that has just been described. Relay 2TN is made slow to drop away by its upper winding being shunted through front contact 28. Although the picking up of relay 2TN opens back contact 21 in the stick circuit for relay 1TNP, the relay 1TNP is still maintained energized through back contact 20 of relay 2TNP at this time.

The picking up of relay 2TN closes an obvious circuit at front contact 29 for the energization of relay 2TNP, and this relay, when picked up, is maintained energized by a stick circuit having energy applied through back contact 30 of relay 1XP connected in multiple with front contact 31 of relay 1XR and through front contact 32 of relay 2TNP and the lower winding of relay 2TNP. This stick circuit maintains relay 2TNP energized until the car for which the storage is provided leaves the car retarder No. 1 so as to permit the exit relay 1XR to be dropped away prior to the dropping away of relay 1XP.

The picking up of relay 2TNP deenergizes the relay 1TNP by the opening of its circuit at back contact 26, and thus relay 1TNP is dropped away (it being assumed that the relay 1TN has been dropped away prior to this time). The dropping away of relay 1TNP opens the stick circuit at front contact 24 by which the relay 2TN has been maintained picked up and thus causes the dropping away of relay 2TN.

When the car has advanced as is indicated in Fig. 2B so that the track section T has become unoccupied in the rear of the car, the track relay TR is picked up, and its back contact repeater relay TP is dropped away by the opening of its circuit at back contact 18.

Upon the picking up of the track relay TR, a circuit is closed for the energization of the track repeater storage relay 2TPS extending from (+), including front contact 33 of relay TR, front contact 34 of relay 2TNP, and upper winding of relay 2TPS, to (-). This relay when picked up is maintained energized dependent upon the continued energization of the storage relay 2TNP by a stick circuit extending from (+), including front contact 35 of relay 2TNP, front contact 36 of relay 2TPS and lower winding of relay 2TPS, to (-).

The function that has been performed by the picking up of the relay 2TPS is to condition Retarder No. 1 Speed Modifier (indicated in block form in Fig. 1A) so that upon the picking up of the check relay 1CK when the car is immediately in approach of car retarder No. 1, the electronic speed modifier is effective to determine the speed of release for car retarder No. 1 in accordance with the performance of the car upon approaching this car retarder. The circuit illustrated in Fig. 1A extending to the block representing Retarder No. 1 Speed Modifier includes back contact 37 of relay 2TPS and front contact 38 of the check relay 1CK in series. The nature of the speed modification in the electronic apparatus is such that it takes place momentarily at the time when the check relay 1CK is picked up provided that the modifying means which includes the charge of a condenser (not shown) is not shunted by a circuit including back contact 37 of relay 2TPS in series with the front contact 38 of relay 1CK. In other words, if the relay 2TPS is picked up prior to the entrance of a car upon the weight detector WD, the shunt circuit connected to the speed modifier is opened by removing the (B-) connection to the shunting circuit through back contact 37 prior to the closure of front contact 38 of the check relay 1CK, and in this manner the retarder No. 1 is permitted to release a car in accordance with performance characteristics that are electronically stored in the Retarder No. 1 Speed Modifier according to a mode of operation fully described in the above mentioned U. S. application of Kendall et al. Ser. No. 513,364 filed of even date with the present application.

Considering further progress of a car so that the car enters upon the weight detector WD as is illustrated in

the track diagram of Fig. 2C, the check relay 1CK is picked up, and upon the picking up of this relay, modification in the control of the speed relay 1S and the anticipation relay 1A is rendered effective so as to render these relays subject to release at respective car speeds selected in accordance with the performance of the car in approaching car retarder No. 1 as to its degree of rolling resistance.

At the time when the check-relay 1CK is picked up, the control of car retarder No. 1 operating mechanism is rendered operative in accordance with the speed and weight of the approaching car. For most cars, the relays 1S and 1A are already in their picked up positions because of the speed of the respective approaching cars being such as to require retardation, and the weight storage relays 1W1 and 1W2 are positioned in accordance with the car weight as registered by the weight detector WD, or any other suitable means.

If it is a heavy weight car that is approaching car retarder No. 1 relay 1W1 is in its dropped away position and relay 1W2 is in its picked up position. Thus, the retarder operating mechanism is provided with energy applied to wire No. 4 to maintain maximum retardation. Energy is applied to wire No. 4 under these conditions through contact 8 of the manual control switch 1RCL, front contact 9 of relay 1CK, front contact 40 of relay 1S, back contact 41 of relay 1W1, front contact 42 of relay 1W2, and front contact 43 of relay 1A.

If it is a medium weight car that is approaching car retarder No. 1, the car retarder is operated to its No. 3 position for applying a lesser amount of retardation in accordance with the application of energy to wire No. 3 through contact 8 of switch 1RCL, front contact 9 of relay 1CK, front contact 40 of relay 1S, front contact 41 of relay 1W1, front contact 44 of relay 1W2, and front contact 45 of relay 1A.

If it is a light weight car that is approaching car retarder No. 1, still lesser retardation is provided because of application of energy to control wire No. 2 through contact 8 of switch 1RCL, front contact 9 of relay 1CK, front contact 40 of relay 1S, front contact 41 of relay 1W1, back contact 44 of relay 1W2, and front contact 46 of relay 1A.

As the speed of the car is reduced, the anticipation relay 1A becomes dropped away before the dropping away of relay 1S, and the shifting of the contacts 45, 46 and 43 of relay 1A to open their front contacts and close their back contacts provides that the operating mechanism of the car retarder No. 1 is operated to its next position of lesser retardation. When the speed of the car is finally reduced to the speed which has been predetermined as being proper for the release of the car from retardation, the relay 1S becomes dropped away, and the dropping away of this relay provides for the opening of the car retarder by the application of energy to wire No. 0 through contact 8 of the switch 1RCL, front contact 9 of relay 1CK, and back contact 40 of relay 1S. The car retarder when thus opened is maintained opened until the dropping away of the check relay 1CK after the car has left the car retarder No. 1 as will be more readily apparent as the description progresses. When relay 1CK becomes dropped away, the circuit described for the application of energy to wire No. 0 is opened at front contact 9 of relay 1CK, and the closure of back contact 69 establishes a circuit that has been described as being normally closed for application of energy to wire No. 4 to restore car retarder No. 1 to its closed position.

As the car proceeds in the track layout to the position indicated in Fig. 2D so that it is substantially close to the exit end of car retarder No. 1, the intensity of the reflected signal from the car in the radar speed responsive apparatus has become so great as to effect the picking up of the relay 1XR as is indicated in the sequence chart of Fig. 3D. The picking up of relay 1XR causes the picking up of its repeater relay 1XP by the energiza-

tion of an obvious circuit closed at front contact 39 of relay 1XR. Relay 1XP is made slow in dropping away by the shunting of its upper winding through front contact 53 for the purpose of providing a clear-out interval upon the dropping away of the relay 1XR after the car has left car retarder No. 1.

When the car has progressed as illustrated in Fig. 2E to the point of having left the car retarder No. 1 entirely, the relay 1XR becomes dropped away, and upon the dropping away of that relay, with the relay 1XP held up by its slow action, energy is removed from the stick circuit that has been described for the relay 2TNP so as to cause that relay to be dropped away. Relay 2TNP when dropped away causes the dropping away of relay 2TPS by the opening of its stick circuit at front contact 35 and pick-up circuit at front contact 34. The control of the relay 1CK is such that this relay is dropped away by the dropping away of relay 1XR or the loss of signal strength, and thus the condition of the relays associated with the control of car retarder No. 1 have been restored to their normal conditions.

A similar mode of operation to that which has been described for the control of car retarder No. 1 is provided for the passage of the car through retarder No. 2. The check relay 2CK is picked up as is disclosed in the above mentioned Kendall et al. application Ser. No. 513,364 filed of even date with the present application upon the picking up of the exit relay 1XR when the car approaches the entrance end of car retarder No. 2. It will be readily recognized that the degree of retardation is selected in the same manner as has been described for car retarder No. 1 by similar circuits which are shown in Fig. 1B, the car retarder No. 2 being opened when the speed of the car has been reduced to a predetermined value so as to cause the dropping away of relay 2S to apply energy to the wire No. 0 for the power operation of the car retarder operating mechanism for car retarder No. 2 to its open position. It will be noted that the car speed at which the speed relay 2S is released is substantially the same as the car speed at which relay 1S is released because the control of relay 2S is by Retarder No. 2 Speed Modifier which is so governed as to provide the same release speed for the relay 2S as the release speed for the relay 1S that is provided by Retarder No. 1 Speed Modifier. This type of control is provided because of electronic storage and transfer means by which the condition of modification set up in Retarder No. 1 Speed Modifier is transferred as is illustrated by the line 47 to Retarder No. 2 Speed Modifier.

Having thus described the mode of operation upon passage of a single car, consideration will now be given as to the mode of operation wherein a second car enters the detector track section T before a first car has passed through car retarder No. 1. Thus the entrance of a second car into the track section T can be considered as taking place under conditions of progress of the first car as illustrated in either Fig. 3C or 3D. The conditions of storage of the presence of the first car will be assumed to have been set up according to a mode of operation as has been heretofore described.

The entrance of the second car into the track section T causes the picking up of the transfer relay 1TN by the energization of a circuit that has been described, and upon the picking up of this relay, the repeater relay 1TNP is picked up, and the relay 1TN becomes released upon the picking up of relay TP by the opening of back contact 13. Because of the relay 2TNP being in its energized position at this time on account of the presence of the first car, back contact 25 of relay 2TNP in the pick-up circuit for the relay 2TN is open, and thus the relay 2TN cannot be picked up at this time in accordance with the picking up of relay 1TNP. Thus the relay 1TNP becomes effective to store the indication of the presence of the second car, and this storage is maintained until the first car has passed out of the car retarder No. 1 so as to permit the dropping away of the exit relay 1XR

prior to the dropping away of its slow repeater relay 1XP. Under these exit conditions the dropping away of relay 2TNP closes back contact 25 and permits the picking up of relay 2TN and the subsequent transfer of the storage for the second car so as to pick up the relay 2TNP and eventually cause the dropping away of the relay 1TNP. The mode of operation upon progress of the second car beyond this assumed condition is substantially the same as that which has been described in detail with reference to the passage of a first car, the relay 2TPS being picked up when the track section T becomes unoccupied in the rear of the second car so as to open back contact 37 prior to the picking up of relay 1CK to close front contact 38 so that there is no shunt applied on the Retarder No. 1 Speed Modifier, thus permitting speed modification to be effective in a manner which has been described.

If the second car were to leave the track section T prior to the first car having left car retarder No. 1, the relay 1TPS would be picked up through front contact 33 of relay TR and front contact 48 of relay 1TNP. This relay when picked up is maintained energized by a stick circuit including front contact 49 of relays 1TPS and front contact 48 of relay 1TNP. The picking up of relay 1TPS is accomplished to store the information that the second car is a short cut and thus should have automatic retarder control according to its performance in approaching the car retarder, as compared to the system of control for the car retarder that will be hereinafter described as being effective upon the passage of long cuts of cars. When the first car has passed out of the car retarder No. 1 so as to permit transfer of the storage of the presence of the second car into the relay 2TNP, the picked up condition of relay 1TPS is also transferred by the picking up of relay 2TPS by a circuit including front contact 50 of relay 1TPS and front contact 51 of relay 2TN. It will be readily apparent that upon the dropping away of relay 1TNP after transfer has been completed, the opening of front contact 48 causes the dropping away of relay 1TPS.

The mode of operation upon the passage of a long cut 40 of cars is substantially the same as has been described except that the track section T never becomes unoccupied prior to the entrance of the cut into the car retarder No. 1 and thus there is no opportunity for picking up the relay 2TPS or the relay 1TPS. With relay 2TPS in its dropped away position at the time when the head end of the cut actuates the weight detector WD, the check relay 1CK is picked up and thus a shunt is applied from (B-) through back contact 37 of relay 2TPS and front contact 38 of relay 1CK to the Retarder No. 1 Speed Modifier which renders the speed modifier ineffective and thereby causes the speed relay 1S to be maintained picked up until the speed of the cut has been reduced to a speed substantially below the speed at which a single car would normally be released. Because of Retarder No. 1 Speed Modifier 55 being shunted at the time of entrance of the cut into car retarder No. 1, there is no modification storage set up in the Retarder No. 1 Speed Modifier to be transferred over wire 47 to Retarder No. 2 Speed Modifier, and thus the speed relay 2S of retarder No. 2 will be released at the same low speed as is provided for the cut by the car retarder No. 1 in accordance with the dropping away of the speed relay 1S.

Although the track relay TR becomes picked up when the rear end of the cut passes out of the track section T, 65 and the relay 2TPS becomes picked up to open back contact 37, this can have no bearing upon the Car Retarder No. 1 Speed Modifier because this modifier is subject to control only at the time when the check relay 1CK is initially picked up upon the first actuation of the weight detector WD. Thus the low release speed for the speed relays 1S and 2S as selected by the modifier having been initially shunted is maintained effective until the cut of cars passes entirely out of the associated car retarders.

Having described one specific embodiment of the present invention as a typical form which the invention may

assume, it is to be understood that this form is selected principally to facilitate the disclosure of the invention, rather than to limit the number of forms the invention may assume, and it is to be further understood that various adaptations, modifications, and alterations may be made to the specific form shown in accordance with the requirements of practice except as limited by the appending claims.

What I claim is:

1. In a car retarder control system, a stretch of railway track including a car retarder and a track section spaced a predetermined distance in approach of the car retarder, speed responsive apparatus for automatically governing the release of said car retarder when a car within the car retarder has reduced its speed to a selected release speed, speed modification means for selecting the release speed of said speed responsive means, and means for rendering said modification means ineffective when the first car of a cut is about to enter the car retarder only provided that said track section has been continuously occupied upon passage of the cut of cars until said first car of the cut has progressed to a point immediately in approach of the car retarder.

2. In a car retarder control system, a stretch of railway track including a car retarder and a track section spaced a predetermined distance in approach of the car retarder, speed responsive apparatus effective when initiated to automatically release the car retarder when a car has reduced its speed to a selected release speed, a device subject to actuation by a car immediately in approach of the car retarder, initiating means including said device for rendering said speed responsive apparatus effective, circuit means for selecting the release speed of said speed responsive apparatus, and means acting upon said circuit means to select a given distinctive predetermined speed of release only provided that said track section is continuously occupied upon passage of a cut of cars until the first car of the cut as progressed to a point wherein said device is actuated.

3. In a car retarder control system, a stretch of railway track including a car retarder and a track section spaced a predetermined distance in advance of the car retarder, radar speed responsive apparatus for automatically governing the release of said car retarder when a car within the car retarder has reduced its speed to a selected release speed, said radar speed responsive apparatus having a directional antenna with a radiation pattern including the area of the trackway in which the car retarder is located, speed modification means for selecting the release speed of said radar speed responsive means, and means for rendering said speed modification means ineffective when a car is about to enter the car retarder only provided that said track section is continuously occupied upon passage of a cut of cars until the first car of the cut has progressed to a point immediately in approach of said car retarder and within the radiation pattern of said antenna.

4. In a car retarder control system, a stretch of railway track including a car retarder and a track switch spaced a predetermined distance in advance of the car retarder, a detector track section for said track switch, speed responsive apparatus for automatically governing the release of said car retarder when a car within the car retarder has reduced its speed to a selected release speed, speed modification means for selecting the release speed

of said speed responsive means, and means for rendering said speed modification means ineffective when a car is about to enter the car retarder provided that said detector track section has been continuously occupied until the first car of a cut of cars has progressed to a point immediately in approach of the car retarder.

5. In a car retarder control system, a stretch of railway track including a car retarder and a track section spaced a predetermined distance in approach of the car retarder, speed responsive apparatus for automatically governing the opening of said car retarder when a car within the car retarder has reduced its speed to a selected release speed, speed modification means for selecting the release speed of said speed responsive apparatus, a track repeater relay, circuit means for energizing said track repeater relay when said track section is unoccupied, said circuit means being rendered effective only provided there is a car between said track section and the exit end of said car retarder, and means for rendering said modification means ineffective when a car is about to enter the car retarder except when said track repeater relay is energized.

6. In a car retarder control system, a stretch of railway track including a car retarder and a track section spaced a predetermined distance in approach of the car retarder, speed responsive apparatus for automatically governing the opening of said car retarder when a car within the car retarder has reduced its speed to a selected release speed, speed modification means for selecting the release speed of said speed responsive apparatus, a track repeater relay, circuit means for energizing said track repeater relay when said track section is unoccupied, said circuit means being rendered effective only provided there is a car between said track section and the exit end of the car retarder, and means selected by said track repeater relay for selectively rendering said modification means effective or ineffective in accordance with whether a short or a long cut of cars is approaching said car retarder.

7. In a car retarder control system, a stretch of railway track including a car retarder and a track section spaced a predetermined distance in approach of the car retarder, speed responsive apparatus for automatically governing the opening of said car retarder when a car within the car retarder has reduced its speed to a selected release speed, speed modification means for selecting the release speed of said speed responsive apparatus in accordance with the performance of a car in approaching the car retarder, a track repeater stick relay, pickup circuit means for energizing said track repeater stick relay when said track section is unoccupied provided that there is a car between said track section and the exit end of the car retarder, stick circuit means for maintaining said track repeater stick relay energized until a car has left the car retarder, and means selected by said track repeater stick relay for selectively rendering said modification means effective or ineffective in accordance with whether a short or a long cut of cars is approaching said car retarder.
